UNITED STATES PATENT OFFICE.

EDWARD STEPHEN STEINHARDT, OF BROOKLYN, NEW YORK, ASSIGNOR OF ONE-HALF
TO DAVID B. APPLEBAUM, OF NEW YORK, N. Y.

TOBACCO AND PIPE POUCH.

Application filed December 18, 1924. Serial No. 756,752.

My invention relates to combined tobacco pouch and pipe pocket, and has for its general object to provide a convenient pouch in which a compartment of ample content is provided for the tobacco, and a conveniently arranged pocket for the pipe, a more specific object being to provide an assemblage of parts so arranged that the tobacco in the pouch will afford cushioning and protection for the pipe.

Figure 1 is a rear elevation of a pouch embodying my invention;

Figure 2 is a horizontal section on the line 2-2 of Figure 1;

Figure 3 is a transverse section on the line 3-3 of Figure 1.

In forming a pouch in accordance with the invention, the same is produced with a front wall 10 and a back wall 11. The front wall 10 is formed with a closure flap 12 for the tobacco compartment, said flap being secured in closed position by co-acting fastener elements 13 on said flap and on said back wall 11 of the pouch.

A partition 14 is provided following generally the lines of a pipe bowl and its stem, and said partition is stitched by a line of stitching 15 to the back wall 11 continuing along the bottom adjacent to the bottom edge of the pouch as at 16, so that a pocket approximately pipe shaped is thus produced. The pipe pocket has a flap 17 integral with an end of the front wall 10, and said flap is adapted to be secured in closed position by mating fastener elements 18 on said flap and on the back wall 11 of the pouch.

With the described arrangement, it will be seen, by comparing Figures 2 and 3, that the tobacco A extends at one side of the partition 14 and about the pipe bowl as at a. Thus the tobacco A is present as a cushion above and partially around the pipe stem and bowl, the cushioning effect of the tobacco being particularly serviceable to protect the stem of the pipe B.

Having thus described my invention, what I claim is:

1. As an article of manufacture, a combined tobacco pouch and pipe pocket, the same comprising a front wall and a back wall, together with a partition, secured at its upper and lower longitudinal edges to one of said walls, said pocket being approximately pipe shaped and opening from an end of the pouch, said pouch embodying a tobacco compartment opening along a side edge of the pouch, and said tobacco compartment extending at one side of the pipe pocket so that the tobacco in said compartment will cushion the pipe.

2. As an article of manufacture, a combined tobacco pouch and pipe pocket, the same comprising a front wall and a back wall, together with a partition, secured at its upper and lower longitudinal edges to one of said walls, said pocket being approximately pipe shaped and opening from an end of the pouch, said pouch embodying a tobacco compartment opening along a side edge of the pouch, and said tobacco compartment extending at one side of the pipe pocket so that the tobacco in said compartment will cushion the pipe; together with separate flaps along the side and an end respectively of the pouch and respectively forming closures for said tobacco compartment and said pipe pocket.

3. As an article of manufacture, a combined tobacco pouch and pipe pocket, the same comprising a front wall and a back wall, together with a partition, secured at its upper and lower longitudinal edges to one of said walls, said pocket being approximately pipe shaped and opening from an end of the pouch, said pouch embodying a tobacco compartment opening along a side edge of the pouch.

EDWARD STEPHEN STEINHARDT.
